SPINDLE BRAKE

Emmett E. Britts, Jr., Kerns, Va., assignor to
Celanese Corporation of America, a corporation
of Delaware

Application September 29, 1942, Serial No. 460,083

5 Claims. (Cl. 57—89)

This invention relates to a spindle brake, and relates more particularly to a portable spindle brake adapted to be carried by the operator in charge of a bank of spindles and to be applied by the operator as required on any spindle of said bank for the purpose of stopping the rotation thereof.

An important object of this invention is the provision of a portable brake for stopping the rotation of a spindle whereby the use of the hand of the operator or the provision of a separate, permanently mounted brake for each spindle is obviated.

Another object of this invention is to provide a portable spindle brake which not only stops the rotation of the spindle but also moves the spindle away from the drive belt and other parts of the machine thus permitting the bobbin to be removed from the spindle without the danger of striking the same on any part of the machine.

A further object of this invention is to provide a portable spindle brake which cooperates with standard spindle machine elements to perform its intended functions.

Other objects of this invention will appear from the following detailed description and drawing.

In the drawing wherein the preferred embodiment of my invention is shown,

Figure 1 is a plan view of the portable spindle brake of my invention shown in operative position, only so much of the spindle structure and bobbin being shown as to demonstrate the operation of the brake, and

Figure 2 is a front elevational view of the spindle brake and spindle structure.

Like reference numerals indicate like parts throughout both views of the drawing.

Referring now to the drawing for a detailed description of my invention, the reference numeral 1 indicates the spindle swing step bracket normally attached to the frame (not shown) of a multiple spindle spinning machine. As is well-known, these multiple spindle spinning machines may consist of banks of 10, 25, 50 or more spindles and they may be employed in winding operations or in winding and twisting operations to produce yarn packages of any desired type. Formed integral with the bracket 1 is a well 2 having an extending rim 3 provided with an upstanding ear 4 containing a locking screw 5. Mounted in the well 2 is a hollow shaft 6 having its free or upper end formed into a swing step 7. A spring 8 and a knurled thumb nut 9 are provided to exert a selected force on the swing step 7 in a clockwise direction. The locking screw 5,

referred to above, locks the thumb nut 9 in the selected position to exert the desired tension on the spring 8.

The free end of swing step 7 is offset and forms a platform 11 with an opening in which a bolster 12 is fixedly mounted. The bolster 12 is provided with a nut or flanged portion 13 adapted to rest on the platform 11 and is provided with a threaded end 14 around which is carried a compression spring 15 held in place by a nut 16. The bolster may be of any of the commercial types and is equipped with bearings and lubricating channels for journaling and lubricating a spindle 17, as is well understood in the art. The spindle 17 has a spool shaped portion or whorl 18 that is adapted to be frictionally driven by a belt 19 when in operative position. A bobbin, pinn, spool or other suitable yarn holder 21 for receiving the yarn is mounted on the spindle 17.

The portable brake of my invention, which is generally indicated by reference numeral 22, is constructed and arranged to cooperate with the shaft 6 to swing the spindle on the arc of the swing step away from the drive belt 19 and to frictionally stop the rotation of the spindle. To this end the brake, which is of bent form, is provided with a pin 23 at its bend 24. The bend 24 in the brake forms the same into a handle 25 and a lever 26 of shorter length than the handle, the handle and lever forming an angle of less than 90° with each other. This construction of the brake prevents the operator's hand from coming into contact with an adjacent spindle. However, for different types of machines the angle may be varied to suit. The free end of the lever arm 26 terminates in an arc-shaped brake shoe 27 that may be lined with leather 28 or other friction material. The pin 23 is adapted to be received with a loose fit in oil hole 29 in shaft 6 wherein it is journaled for pivotal movement.

To operate the brake, the operator inserts the pin 23 of the brake in the oil hole 29 of the hollow shaft 6 with the lined face 28 of the brake frictionally engaging the whorl 18. The handle 25 is moved counter-clockwise as viewed in Figure 1. This action swings the spindle away from the drive belt, frictionally stops its rotation and positions it so that the yarn package may be removed therefrom without its striking yarn guides, frame or other parts of the spinning machine.

It is to be understood that the foregoing detailed description is merely given by way of illustration and that many variations may be made therein without departing from the spirit of my invention.

Having described my invention, what I desire to secure by Letters Patent is:

1. A portable brake adapted to stop the rotation of a spindle assembly provided with an oil well and swing the spindle on the arc of its swing step, comprising a handle, a lever arm extending at an angle from the handle, a brake shoe at the free end of said lever arm, and a pin at the junction of the handle and lever arm, said pin being adapted to be inserted in the oil well of a spindle swing step.

2. A portable brake adapted to stop the rotation of a spindle assembly provided with an oil well and swing the spindle on the arc of its swing step, comprising a handle, a lever arm extending at an angle of less than 90° from the handle, a brake shoe at the free end of said lever arm, and a pin at the junction of the handle and lever arm, said pin being adapted to be inserted in the oil well of a spindle swing step.

3. A portable brake adapted to stop the rotation of a spindle assembly provided with an oil well and swing the spindle on the arc of its swing step, comprising a handle, a lever arm extending at an angle from the handle, an arc shaped brake

shoe at the free end of said lever arm, and a pin at the junction of the handle and lever arm, said pin being adapted to be inserted in the oil well of a spindle swing step.

5. 4. A portable brake adapted to stop the rotation of a spindle assembly provided with an oil well and swing the spindle on the arc of its swing step, comprising a handle, a lever arm extending at an angle from the handle, a brake shoe at the free end of said lever arm, and a pin at the junction of the handle and lever arm, said pin being adapted to be inserted with a loose fit in the oil well of a spindle swing step.

15. 5. A portable brake adapted to stop the rotation of a spindle assembly provided with an oil well and swing the spindle on the arc of its swing step, comprising a handle, a lever arm extending at an angle of less than 90° from the handle, an arc shaped brake shoe at the free end of said 20 lever arm, a lining on said brake shoe, and a pin at the junction of the handle and lever arm, said pin being adapted to be inserted in the oil well of the spindle swing step.
